ABSTRACT OF THE DISCLOSURE

A bolster pad for disposition in the sulciform region of the toes and attached directly to the foot of the user to provide relief for afflicted toes and also exercise for the foot for both the alleviation and prevention of adverse conditions in the region in the metatarsal arch and toes of the foot, although other uses may be apparent to those skilled in the art.

Frequently, at middle age or thereafter there is a tendency for the adipose tissue beneath the metatarsal heads to move forwardly into the sulciform regions of the toes, and consequently the toes tend to lose their gripping power. Such condition encourages the development of adverse metatarsal symptoms which can, in many cases, be avoided or prevented by utilizing some means, such as the instant invention, to not only maintain the adipose tissue in its proper location but also provide the toes with exercise of a beneficial character to tone the foot and retain it in a vitalized condition.

With the use of a bolster pad, such as the instant invention, placed in the sulciform region of the toes, the resilient cushioning and supporting means afforded by the pad are in position to be gripped by the toes at each step of the user, and the toes are subjected to substantially constant exercise while the user is walking or otherwise changing positions of his feet, and this exercise aids in the reactivation and revitalization of weak foot muscles and strained ligaments, giving beneficial results to the foot, relieving arch sag, strengthening and raising the metatarsal arch, and performing similar corrective and alleviating functions.

With the foregoing in mind, it is an important object of the instant invention to provide an economical and efficient bolster pad, simple in construction, one that is effective, and which may be laundered at will.

Also an object of this invention is the provision of a simple form of bolster pad in which the pressure sustaining property of the part of the pad underlying toes, may be varied at will.

Another object of this invention is the position of a bolster pad that may be made entirely in a simple manner from a single tubular member having an inner layer of stretchable fabric and an outer thicker layer of thermoplastic foam or the equivalent.

It is also an important object of this invention to provide a new and novel method of making a bolster pad.

While some of the more salient features, characteristics and advantages of the instant invention have been above pointed out, others will become apparent from the following disclosures, taken in conjunction with the accompanying drawings, in which:

FIGURE 1 is a perspective view of a piece of material from which a bolster pad incorporating principles of the instant invention may be made;

FIGURE 2 is an exploded view of the structure of FIGURE 1 showing steps in the process of making a pad therefrom;

2

FIGURE 3 is a top perspective view of a finished bolster pad;

FIGURE 4 is a fragmentary diagrammatic view illustrating the use of the bolster pad on the human foot;

FIGURE 5 is an enlarged perspective view of the pad emphasizing the side and one end of the pad;

FIGURE 6 is a greatly enlarged central vertical sectional view taken substantially as indicated by the line VI—VI of FIGURE 5; and

FIGURE 7 is a greatly enlarged transverse vertical sectional view through the pad taken substantially as indicated by the line VII—VII of FIGURE 5.

As shown on the drawings:

The instant invention may perhaps best be introduced by way of the method of making it, as illustrated more particularly in FIGURES 1, 2 and 3. At the outset, a tube 1 of cushioning material is selected of a length in accordance with the size of resilient device desired, since the bolster pad may be made in various sizes to accommodate the feet of children, women and men. The tube 1 preferably consists of an inner layer 2 of a fabric stretchable to some extent, such as a woven gauze or the like, and an outer layer 3 of cushioning material such as a foam, polyvinyl chloride, polyurethane, polyurethane impregnated with a vinyl or acetate substance, or any equivalent material capable of producing an electronically heat sealable foam is highly satisfactory. The foam 3 is, of course, much thicker than the lining or inner layer 2, and the foam may have intercommunicating cells for ventilative purposes. Such material will have a soft gentle and somewhat clinging feel when applied against the human foot. The resultant laminate construction is stretchable to an extent sufficient for proper application to a foot of the finished article, the stretch of the foam being limited to the maximum stretch of the fabric lining. The tube 1 may be made by casting or curing the foam directly to the fabric lining, which lining may be initially woven in tubular form and then the foam applied or the lining may be in flat condition with the foam applied and a tube formed from the same.

Substantially half-tubular or larger sections 4 and 5 are removed from the end portions of the tube, as indicated in FIGURE 2. This leaves curvate portions 6 and 7 remaining on opposite ends of a central completely tubular portion 8 which has remained intact. The remaining end portions 6 and 7 may then be folded over the tubular portion 8 and heat sealed together in end-to-end abutment as indicated at 9. The two end portions thereby form a toe loop for the reception of a plurality of toes of the foot when the device is applied to the foot.

However, it may be desired to render the tubular portion 8 somewhat firmer or denser insofar as its cushioning property is concerned, and to that end one of the removed sections, section 4 for example, may be folded and inserted within the tubular portion 8 of the device prior to the joining of the remaining end portions 6 and 7. It will be seen that the end portions 6 and 7 preferably overlie the ends of the opening in the tube, and consequently will retain the inserted piece 4 within the tubular section 8 against accidental dislodgement.

Insertion of the section 4 within the tubular portion 8 after being folded longitudinally as indicated at 10 in FIGURE 7, will result in the section 4 substantially filling the inside of the tubular section 8, thereby adding to the firmness with which that section will press against the toes or, in other words, will render the portion 8 less yieldable to foot pressure thereon. If both sections 4 and 5 are inserted in the section 8 the pad will be still more firm.

In FIGURE 4, I have illustrated the application of the device to a human foot 11, with the tubular body portion 8 of the device disposed in the sulciform region of the three intermediate toes 12, the toe loop formed by the

3

end portions 6 and 7 overlying the toes. In this position the part 8 of the bolster pad will aid in maintaining adipose tissue of the metatarsal heads in proper position beneath those metatarsal heads and at every step of the user will cause a gripping of the part 8 by the toes of the foot, thereby providing comfortable but compulsory and beneficial exercise of the foot during use of the bolster pad. As the condition of the foot improves, and the full effect of the device with the insert 4 therein may become no longer necessary, the toe loop will stretch sufficiently to permit the removal of the section 4 from the tubular portion 8 and thereby render the device more yieldable to foot pressure. The bolster pad is therefore adjustable as to its pressure resisting property at will and depending upon the condition of the particular foot.

Should there be a hammer toe condition on the third toe of the foot, the device may be mounted in position to alleviate that condition also, by having the toe loop go over the second toe, under the third toe, and over the fourth toe of the foot. When mounted on the foot in this position, the third toe will have the benefit of the underneath support of a portion of the toe loop in addition to the tubular portion 8 of the bolster pad, tending to provide a straightening effect upon the hammer toe, without lessening the effectiveness of the device in any other regard.

It will be noted that it is not essential that the removed sections 4 and 5 from the initial tube 1 be of the same length, but one may be longer than the other, depending upon where it is desired to dispose the heat seal seam 9 when the device is applied to the foot. Also, there may be only one removed section from side of the remaining tubular portion 8, and the single remaining end portion of the device may alone form the toe loop with the outer end thereof secured to the tubular portion 8 directly. It is only necessary that the toe loop be formed of sufficient length to loosely overlie the tubular portion 8 and provide room consistent with a slight stretching of the toe loop to accommodate the toes for the particular size device being made.

It will be understood that modifications and variations may be effected without departing from the scope of the novel concepts of the present invention.

I claim as my invention:

1. The method of making a bolster pad for application to the human foot including the steps of,

4

removing substantially half sections from each end portion of a tube of cushioning material leaving the central portion of the tube intact, and folding the remaining end portions of the tube over the intact central portion and securing the ends thereof together to form a toe loop.

2. The method of claim 1 including the additional step of inserting at least part of the removed half sections within the intact central portion.

3. The method of claim 1 wherein the cushioning material is thermoplastic foam, including the step of heat sealing the ends of the remaining end portions together.

4. A bolster pad for application to the human foot, including

a tubular portion of cushioning material, a toe loop integral with said tubular portion and of the same material, an insert in said tubular portion also of cushioning material, and said toe loop extending over the ends of said tubular portion to retain said insert within said tubular portion.

5. A bolster pad for application to the human foot, including

a tubular portion of cushioning material, a toe loop integral with said tubular portion, an insert in said tubular portion of the same material, said insert being folded lengthwise to substantially fill the inside of said tubular portion.
